FIG. 1.

FIG. 2.

CHRISTIAN ARPAD JAKOBB
INVENTOR

BY Thomas J. Wallace
ATTORNEY

UNITED STATES PATENT OFFICE

132,718

DESIGN FOR A BROOCH OR SIMILAR ARTICLE

Christian Arpad Jakobb, Bayside, Long Island,
N. Y.

Application December 2, 1941, Serial No. 104,434

Term of patent 3½ years

To all whom it may concern:

Be it known that I, Christian Arpad Jakobb, a citizen of the United States of America, residing in Bayside, Long Island, county of Queens, and State of New York, have invented a new, original, and ornamental Design for a Brooch or Similar Article, of which the following is a specification, reference being had to the accompanying drawing, forming part thereof, wherein,

I claim:

The ornamental design for a brooch or similar article, substantially as shown.

CHRISTIAN ARPAD JAKOBB.
